UNITED STATES PATENT OFFICE.

CARL HORIX, OF CLEVELAND, OHIO.

METALLIC REINFORCEMENT IN CONCRETE STRUCTURAL WORK.

No. 845,787.

Specification of Letters Patent.

Patented March 5, 1907.

Application filed January 22, 1906. Serial No. 297,191.

To all whom it may concern:

Be it known that I, CARL HORIX, a citizen of the United States, residing at Cleveland, in the county of Cuyahoga and State of Ohio, have invented certain new and useful Improvements in Metallic Reinforcements in Concrete Structural Work; and I do declare that the following is a full, clear, and exact description of the invention, which will enable others skilled in the art to which it appertains to make and use the same.

My invention relates to metallic reinforcements for concrete structural work of various kinds; and the invention consists in a reinforcement of a truss shape or form in cross-section, as herein shown, having a plurality of tensile strands and two series of stress portions or members substantially A shape in elevation connecting said strands, all substantially as shown and described, and particularly pointed out in the claims.

In the accompanying drawings, Figure 1 is a perspective view of a section or piece of a complete reinforcement according to my present invention, and Fig. 2 is a cross-section thereof. Fig. 3 is a perspective view of a short section or piece of the reinforcement embodying a modification of the upper strand, as compared with Figs. 1 and 2.

As thus shown the reinforcement is constituted with two base-strands A, formed of two or more wires or their equivalent twisted or wound tightly together. Said strands or chords are spaced apart from one another relatively, as shown. A single intermediate strand B, likewise constituted of a plurality of wires, as shown in Figs. 1 and 2, and one wire C, as shown in Fig. 3, and the sides or stress members of the reinforcement are formed with separate wires D and E. These wires are bent to approximately V shape, as seen in side elevation, and have opposite portions 2 and 3 at an inclination to both lines of strands viewed lengthwise and also inclined to about the same degree transversely, as seen in cross-section, Fig. 2. However, in this latter view only one stem of each wire D and E is shown, and said wires cross each other back and forth at each apex or crossing-point 4, first to one side and then to the other alternately at an inclination of approximately forty-five degrees to the axis of the strands and are fixedly engaged with both the upper and the lower strands in manner as shown or equivalently.

The so-called "upper" or "intermediate" strand B, Fig. 1, is shown as more closely woven or twisted than the base-strands, though it need not be, and also of smaller wire, 60 because the principal strain comes on the base-strand and a simple modification of this construction is seen in Fig. 3, wherein a single wire C serves the purpose of the strand for uniting the side wires. This latter wire is provided 65 with loops or eyes c at the crossing-points for the side wires D and E, which are threaded through these loops from opposite sides, and said wire C thus serves as an effective tie for the several side wires or stress members of the reinforcement at their crossing-points the full length of the reinforcement. In point of fact, the connecting or tie strand or chord may be very much lighter than the tensile strands A and B, because the strain 70 naturally comes on the tensile strands and the other strand is designed more particularly to provide a running connection from crossing to crossing of the side wires and to make the reinforcement complete in this 75 particular in so far as such connection between the side wires may be needed. However viewed and in whatever relation or use the reinforcement may be employed it has the exceptional value of a truss in point of 80 strength and resistance. Hence it is especially advantageous for all overhead work—such as arches, ceilings, girders, roofs, floor-work, and the like—but may also be variously employed, as in columns, posts, 85 railroad-ties, and generally wherever concrete work of any considerable proportions is employed and added strength is desired.

What I claim is—

1. As a new article of manufacture, a reinforcement for columns, fence-posts and the like, substantially V-shaped in cross-section and having two base-strands and a single centrally-disposed intermediate strand, all of said strands constructed of a plurality of 90 wires twisted together, and side wires bent into a series of V-shaped formations and interwoven with both the said base-strands and the said intermediate strands, and said side wires crossing each other at approximately right angles in the said intermediate strand and running alternately through the said base-strands.

2. A reinforcement for fence-posts and the like formed of wire and having two base-strands and a centrally-disposed intermediate strand, and wire sides for said rein-

forcement bent into a series of V-shaped formations running with said sides and crossing each other from one side to the other at right angles in the intermediate strand and 5 interlocked therewith and with said base-strands, said reinforcement being V-shaped in cross-section.

In testimony whereof I sign this specification in the presence of two witnesses.

CARL HORIX.
